Paul B. Saunders, Jr., Aurora, Ill.

Application February 15, 1950, Serial No. 144,224

2 Claims. (Cl. 74—342)

1

This invention relates to an improvement in the operating mechanism of a toy.

An important object of the invention is to provide a toy with means for automatically changing the direction of its movement.

Another object of the invention is to provide a toy having contact members and means operable by said members to vary the direction of movement of the toy.

A further object of the invention is to provide a toy having at its ends obstacle contacting members with means operable thereby for reversing the direction of movement of the toy.

Still another object of the invention is to provide a toy which is simple in design, rugged in construction and economical to manufacture.

Other objects and advantages of the invention will be apparent during the course of the following description of an embodiment illustrated by way of example in the accompanying drawings in which:

Figure 1 is a side view in elevation of a toy embodying principles of this invention and showing in dotted lines the outline of a vehicle body;

Figure 2 is a bottom plan view of the toy shown in Figure 1;

Figure 3 is a top plan view thereof showing the relative position of parts effecting movement of the toy in one direction;

Figure 4 is a similar view showing the relative position of operating parts when the reversing mechanism has been actuated to change the direction of movement of the toy; and

Figure 5 is a horizontal cross-sectional view, with parts in elevation, taken along the line 5—5 of Figure 3.

The improvements embodied in this invention are shown in the drawings, by way of example, in association with a wheeled toy vehicle. It is to be understood, however, that this invention may be used with other toys, whether driven by a propeller or other means.

In the present instance, the invention is shown in Figure 1 applied to an automobile having a body 10 illustrated by dotted lines, and a chassis 11 illustrated in full lines. The chassis includes a frame 12 mounted on a front axle 13 having wheels 14, 14 thereon and a rear axle 15 similarly equipped with wheels 16, 16. The front axle assembly is connected to the frame 12 by means of a truck 17 the sides 18 and 19 of which are apertured to loosely receive therethrough the axle 13.

It will be noted that the side edges 20 and 21 of the frame 12 are upturned slightly to provide a shallow trough. This permits an actuator mem-

ber 22 to slide within the frame 12 between the frame and the truck 17. Elongated slots 23, 24 and 25 in the frame respectively receive therethrough flat headed pins 26, 27 and 28 carried by the actuator member 22. Coaction of the pins and slots limits relative endwise movement of the actuator member on the frame.

The rear axle assembly is mounted on the frame by means of a sub-frame 29. As best shown in Figures 3 and 4, the sub-frame is box-like in appearance and is mounted directly over the actuator member 22.

Journalled in the side walls of the sub-frame is the rear axle 15 and other shafts which carry gears and pinions connecting a flywheel 30 to the rear axle for driving the same. The flywheel is mounted on one end of a shaft 31 with a pinion 32 on the opposite end thereof. A first idler shaft 33 has mounted on an end thereof a compound gear having a gear portion 34 and a pinion portion 35. The gear portion 34 is in constant meshing engagement with the pinion 32.

An actuator shaft 36 is journalled in the side-walls of the sub-frame in spaced relation to the idler shaft 33. One end of the shaft 36 extends beyond the sub-frame, is journalled in an actuator support 37, and has fixedly mounted thereon a gear 38 positioned between the support 37 and the nearest sidewall of the sub-frame. As best shown in Figure 5, the support 37 has a bottom leg 37a which slidably fits within guide slots 39 and 40 in the sidewalls of the sub-frame. This permits the support to be shifted in a horizontal direction in which the upright leg 37b is movable toward and away from the sub-frame. The hub 41 of the gear 38 is peripherally grooved adjacent its outer end to receive therein the forked end 37b of the actuator support. Such an arrangement permits the actuator to shift the shaft 36 in an axial endwise direction while permitting rotation of the shaft.

It will be noted that the pinion 35 is sufficiently wide to permit the gear 38 to be shifted laterally with shaft 36 while maintaining constant meshing engagement therebetween. The limits of the shifting of the gear 38 on the pinion 35 is shown in Figures 3 and 4.

A second idler shaft 42 is positioned between and slightly below shafts 33 and 36. A compound pinion on the shaft has spaced toothed portions 43 and 44 with a connecting hub 45. It will be noted in Figure 4 that the hub 45 is wider than a pinion 46 carried by the actuator shaft 36. This is for a purpose to be more fully described hereinafter.

A third idler shaft 47 (Figure 5) is journalled

in the sidewalls of the sub-frame and has a wide pinion 48 thereon adjacent one end. This pinion is between and in constant meshing engagement with the pinion 43 and a driving pinion 49 mounted on the vehicle rear axle 15.

The actuator support 37 is shifted laterally of the vehicle frame by movement of the actuator member 22 in a lengthwise direction. As best seen in Figures 2 and 4, the actuator member is provided with a slot 50 which is disposed generally in an angular direction relative to the longitudinal axis of the actuator member. A headed pinion 51 is carried by the leg 37a of the actuator support 37 and the shank of the pin seats within the slot 50.

During movement of the vehicle, should the rear bumper 52 or the front bumper 53 encounter any obstruction such as a wall, a piece of furniture, or the like, the force of the impact moves the actuator member backward. As seen in Figures 2 and 3, movement of the actuator member forwardly on the vehicle moves pin 51 to the rear end of the slot 50 and thereby displaces the pin to one side of the longitudinal axis of the vehicle frame. This displacement of the pin simultaneously effects a lateral movement of the actuator support 37. In Figure 3 is shown the lateral movement of the actuator support in one direction and in Figure 4 lateral movement thereof in the opposite direction.

When the actuating member 22 is moved forward (Figure 3) the actuator support 37 is shifted to the right which brings pinions 44 and 46 into meshing engagement. Motion of the flywheel 30 is transmitted to the rear wheels 16, 16 of the vehicle successively through pinion 32, gear 34, pinion 35, gear 38, and pinions 46, 44, 43, 48 and 49. Rotation of the flywheel in a clockwise direction effects forward movement of the vehicle.

On contact of the front bumper 53 with an obstruction, the actuating member is moved to the rear and by cooperation of the slot 50 and pin 51 the actuator support 37 is moved to the left or toward the sub-frame. In this relative position, the pinion 46 is moved out of engagement with pinion 44 and into engagement with pinion 48. This eliminates the pinion 44 from the chain of power transmission thereby effecting a reversal of rotation of the vehicle wheels and a change in direction of movement of the vehicle.

On contact with the rear bumper 52 with an obstruction, reversal of movement of the vehicle is automatically effected. It will be obvious that movement of the vehicle in backward and forward directions will continue so long as rotation of the flywheel is sustained.

Rotation at high speed of the flywheel is accomplished by pushing the vehicle rapidly in relatively short strokes several times over a surface such as a floor. As the vehicle is pushed more rapidly with each stroke, a faster spin is imparted to the flywheel through the gear train. The inertia of the flywheel weighted at its periphery tends to maintain and prolong movement of the vehicle over a floor or other surface.

Although the toy described herein is a wheeled vehicle, it is apparent that the reversing mechanism can equally well be applied to a toy driven by a propeller, such as an airplane or boat.

The invention has been described herein more or less precisely as to details, yet it is to be un-

derstood that the invention is not limited thereby, as changes may be made in the arrangement and proportion of parts and equivalents may be substituted, without departing from the spirit and scope of the invention.

I claim as my invention:

1. Reversing mechanism for a toy, comprising a wheel mounted frame, a first actuator mounted on said frame for reciprocal movement thereon in one direction thereof and having a slot extending angularly with respect to the path of said movement, a second actuator mounted on said frame for reciprocal movement angularly with respect to said first actuator and having a pin engaging within said slot, the slot and pin arrangement being such that the reciprocal movement of one actuator effects reciprocal movement of the other, a shaft mounted for rotation and endwise movement and having a peripheral groove, an actuating member operable with one of said actuators and seated in said peripheral groove to permit the shaft to rotate, a driving gear carried by and rotatable with said shaft, and spaced driven gears separately engageable by the first mentioned gear, said driving gear being movable with the shaft by the actuating member into and out of engagement alternately with said spaced gears whereby to change the direction of movement of said toy.
2. Reversing mechanism for a toy, comprising a wheel mounted U-shaped frame, a first actuator mounted in said frame for reciprocal movement lengthwise thereof and having a slot extending angularly with respect to the path of said movement, a second actuator mounted on said frame for reciprocal movement laterally thereacross and having a pin engaging within said slot, relative movement of the pin and slot effecting reciprocal movement of one actuator by reciprocal movement of the other, a shaft having a peripheral groove adjacent one end thereof, bearings mounting said shaft for rotation and endwise movement, a forked member operable with said second actuator and seated in said peripheral groove to permit the shaft to rotate, a driving gear carried by and rotatable with said shaft, a driven gear through which the toy is actuated, and spaced idler gears one of which is in meshed engagement with the driven gear, said driving gear being movable with said shaft through the forked member by said second actuator into and out of engagement alternately with said driven gear and the other of said idler gears.
